(57) **CLAIM**

The ornamental design for a cosmetic package, as shown and described.

DESCRIPTION

FIG. 1 is a perspective view of a cosmetic package showing our new design;

FIG. 2 is a front view thereof;

FIG. 3 is a back view thereof;

FIG. 4 is a top plan view thereof;

FIG. 5 is a bottom view thereof;

FIG. 6 is a left side view thereof;

FIG. 7 is a right side view thereof;

FIG. 8 is a cross sectional view taken along 8—8 of FIG. 2 thereof; and,

FIG. 9 is a front view thereof with a series of cosmetic packages being shown in broken lines for illustrative purposes only and forming no part of the claimed design.
